[57] **CLAIM**

The ornamental design for a multi-function radio pager charger, as shown and described.

DESCRIPTION

FIG. 1 is a front elevational view of a multi-function radio pager charger showing our new design;

FIG. 2 is a top plan view thereof;

FIG. 3 is a right side elevational view thereof, the left side being a mirror image;

FIG. 4 is a rear elevational view thereof;

FIG. 5 is a bottom plan view thereof;

FIG. 6 is a front and upper right perspective view thereof;

FIG. 7 is a front elevational view of a second embodiment of the multi-function radio pager charger illustrated in FIG. 1;

FIG. 8 is a top plan view of the embodiment disclosed in FIG. 7;

FIG. 9 is a right side elevational view of the embodiment disclosed in FIG. 7, the left side being a mirror image;

FIG. 10 is a rear elevational view of the embodiment disclosed in FIG. 7;

FIG. 11 is a bottom plan view of the embodiment disclosed in FIG. 7;

FIG. 12 is a front and upper right perspective view of the embodiment disclosed in FIG. 7;

FIG. 13 is a rear and lower left perspective view of the first embodiment as disclosed in FIGS. 1-6; and,

FIG. 14 is a rear and lower left perspective view of the second embodiment as disclosed in FIGS. 7-12.
